UNITED STATES PATENT OFFICE

136,019

DESIGN FOR AN ATTACHABLE SHAPING MACHINE OR THE LIKE

Rudolph F. Bannow, Easton, and Magnus Wahlstrom, Bridgeport, Conn.

Application May 3, 1943, Serial No. 110,103

Term of patent 14 years

To all whom it may concern:

Be it known that we, Rudolph F. Bannow and Magnus Wahlstrom, citizens of the United States and residents respectively of Easton, in the county of Fairfield and State of Connecticut, and of Bridgeport, in the county of Fairfield and State of Connecticut, have invented a new, original, and ornamental Design for an Attachable Shaping Machine or the like, of which the following is a specification, reference being had to the accompanying drawings forming part hereof.

Figure 1 is a plan view, Figure 2 is a front view, Figure 3 is a left side view, and Figure 4 is a right side view of an attachable shaping machine or the like showing our new design.

We claim:

The ornamental design for an attachable shaping machine or the like, substantially as shown.

RUDOLPH F. BANNOV.
MAGNUS WAHLSTROM.
